ICICLE MELTER

Persifor G. Spilsbury, Phoenix, Ariz., assignor to
 Anaconda Wire & Cable Company, New York,
 N. Y., a corporation of Delaware

Application September 19, 1936, Serial No. 101,583

2 Claims. (Cl. 108—26)

This invention relates to means for melting and, therefore, preventing the retention of icicles along the overhanging portions of roof structures.

5 In northern sections of this country, it is known that damage to building structures and possible injury to persons is likely to result because of the formation of large icicles along the edges of roofs or gutters on various building structures. One 10 object of the present invention is to provide means for preventing the formation of such icicles or to melt off the same in the event they should fall. The invention will be fully apparent from the following specification when read in connection with the accompanying drawing.

In the drawing—

Fig. 1 exemplifies a flat roofed structure of a masonry type of building with my invention applied thereto; Fig. 2 is a sectional elevation of a 20 frame building showing the application of my invention thereto; Fig. 3 is an enlarged sectional detail of a portion of Fig. 2; Fig. 4 is a perspective view diagrammatically showing a circuit arrangement and certain circuit controlling devices; and 25 Fig. 5 is a detailed view of an alternative embodiment of the invention.

Referring in detail first to Fig. 1, 10 represents an upright wall of a building structure and 11 the roof portion thereof. A cornice or other overhanging element is secured to the roof in any suitable approved manner. In the embodiment of the invention shown in Fig. 1, I provide a flashing including an upper flange 13, one extremity of which overlaps the roof structure and 35 extends under the roofing sheets 14. This flashing includes a substantially upright wall 15 and an inwardly bent portion 16, part of which is bent around, indicated at 17, to form a chamber for enclosing a heating element 18.

40 In the embodiment illustrated in Fig. 2, the frame building includes an upright wall 10^a, roof rafters 11^a carrying roofing boards 11^b and shingles 11^c. In this case, the upper flange 13^a of the sheathing extends under the lower course 45 of shingles and the chambered portion 17^a is formed at the lower extremity of the upright portion 18^a. Extending obliquely upward from the portion 17^a, there is an extension 18^b which is flanged downwardly as at 18^b for engagement 50 with the side wall.

This chambered portion carries a heating element, indicated at 18, which is substantially the same as that shown in the embodiment of the invention illustrated in Fig. 1.

55 As shown in Fig. 3, the heating element con-

sists of a high resistance electrical conductor surrounded by suitable insulating material 19.

The heating element is adapted to be energized by current supplied from a suitable source. In the drawing, I have shown positive and negative 5 line wires 20 and 21 and a manually operated switch 22 constituting a master control. The circuit will preferably include a variable resistance indicated at 23. Preferably, I will also include in the circuit a thermostat 24 of known 10 construction, which will be effective to make or break the circuit through the heating element, when predetermined temperatures are reached. In some cases, I also consider it advantageous to provide means which will permit the energization 15 of the heating element only at predetermined time intervals. For example, to this end, I will provide a clock operated switch 25, which may be so set that icicles can be melted only during the evening hours, when it is very unlikely that there 20 will be persons, in the neighborhood of the building, who might be hurt by the melting off of the icicles, which might form.

From the disclosure, it will be apparent that the device can be so operated that current will flow 25 through the heating element at all times when the temperature is below a certain point. The element can be so designed that sufficient heat will be generated to prevent the formation of icicles along the cornice or coping of a building. 30 Or, alternatively, the flow of current to the heating element can be controlled manually at intermittent times so as to melt off any icicles, which may have accumulated during the time the element was not in operation.

35 The heating element is preferably enclosed in copper tubing or housing, such as indicated at 26. Various materials may be used for the flashing, but I preferably use either copper, brass, or like metals because of their high heat conductivity 40 and relatively low cost and resistance to destruction by the elements.

In Fig. 5, I have illustrated an alternative embodiment of the invention wherein the heating element 18 is mounted in juxtaposition to an 45 ordinary sheet metal gutter 27 mounted in position to receive water falling from the roof. It is clear that with the heating element juxtaposed to the gutter, as illustrated, the formation of ice in the gutter with resultant clogging would be 50 adequately prevented.

While I have described quite specifically the particular embodiments of the invention herein illustrated, it is to be understood that various modifications may be made without departure 55

from the invention as defined in the appended claims.

What I claim is:

1. A roof structure including a flashing member formed with a chambered portion at the low point of the flashing, localizing the dripping and enclosing a heating element effective to prevent the retention of icicles.

2. A roof structure including a metal flashing having a flanged part which overlaps the roof end and an upright part extending downwardly therefrom and formed adjacent its lower extremity with a chambered portion forming an integral enclosure for a heating element effective to prevent the retention of icicles.

PERSIFOR G. SPILSBURY.
